CLOTHES HAMPER OR SIMILAR ARTICLE

Jon W. Hauser, St. Charles, Ill., assignor to Hawley Products Company, St. Charles, Ill., a corporation of Delaware

Application February 16, 1955, Serial No. 34,532

Term of patent 14 years

(Cl. D58—4)

FIG. 1

FIG. 3

Fig. 1 is a plan view of a clothes hamper or similar article embodying my new design;

Fig. 2 is a front elevational view of the clothes hamper or similar article; and

Fig. 3 is a side elevational view of the clothes hamper or similar article.

I claim:

The ornamental design for clothes hamper or similar article, substantially as shown.
